HATCH CONSTRUCTION

Loyd E. Cartmill, Palo Alto, Calif.

Application February 12, 1940, Serial No. 318,511

4 Claims. (Cl. 108—5.4)

This invention relates to hatch constructions for metal car roofs, particularly hatch constructions of the kind wherein a hatch cover seats on the upper end of a hatch frame. The principal objects of the present invention are to prevent particles of ice, cinders or other material from lodging on the seat for the hatch cover and preventing complete closing of the hatch cover and causing damage to the seat engaging gasket or padding carried by said cover, and to simplify and strengthen the hatch construction and cheapen the cost thereof. The invention consists in providing the upper end of the hatch frame with a hatch cover seat which surrounds the opening defined by said frame and slopes inwardly and downwardly toward said opening. It also consists in embodying said seat in an exterior downwardly opening hollow rim portion at the upper end of said hatch frame, and it also consists in the parts and in the combinations and arrangements of parts hereinafter described and claimed.

In the accompanying drawing, which forms part of this specification and wherein like symbols refer to like parts wherever they occur—

Fig. 1 is a plan view of the end portion of a metal car roof provided with a hatch construction embodying my invention,

Fig. 2 is a vertical partial cross-section on the line 2—2 in Fig. 1,

Fig. 3 is a partial longitudinal section on the line 3—3 in Fig. 1,

Fig. 4 is an enlarged fragmentary section similar to Fig. 2 through one side of the hatch construction; and

Fig. 5 is an enlarged fragmentary section similar to Fig. 3 through one side of the hatch construction.

In the accompanying drawing, my invention is shown embodied in a metal car roof comprising end and intermediate roof sheets 1 and 1a, respectively, that extend from side plate 2 to side plate 2 of the car with their eaves ends resting on and rigidly secured to metal roof supports 3 bolted to the tops of the wooden side plates. In the side plate construction shown, the side sheathing 4 terminates below the top of the side plate, the roof sheets have depending eaves flanges 5 that overhang a fascia board 6, and the side wall insulation 7 is clamped to the side plate by means of a cleat 8 interposed between said insulation and said fascia board and side sheathing.

The roof sheets are provided along their adjacent margins with upstanding flanges 9 that are straddled by a seam cap 10 that is riveted or

otherwise secured to said flanges and to the roof supports 3. At the end of the car the end roof sheet 1 is supported on and riveted or otherwise secured to the outstanding top flange of an end angle 11 whose depending flange is rigidly secured to a metal end plate 12.

The roof is provided with one or more hatchways that lead downwardly into the interior of the car through the end or hatch sheet and a suitable framework located therebelow. Said framework preferably comprises spaced parallel frame or carline members 13 connected by spaced cross-frame members 14. The carline members extend from side plate to side plate with their ends secured thereto by suitable brackets 15. The carline members and the cross-members preferably comprise metal angles arranged with their top flanges facing outwardly and with their side flanges converging downwardly.

Each hatchway is provided with a metal hatch frame comprising a hopper portion 16 that extends downwardly through the opening defined by the frame members 13 and 14 with its downwardly converging sides conforming to the inclined sides thereof. The hatch frame extends above the general level of the roof where it is flanged outwardly and thence downwardly to form an exterior downwardly hollow rim portion 17 at the upper end of said frame. The depending outer wall of the rim 17 of the hatch frame inclines downwardly and outwardly; and the end roof or hatch sheet 1 is provided above the opening defined by the frame members 12 and 13 with an opening of substantially the same shape as but larger than said rim and with an upwardly and inwardly inclined edge flange 18 along said opening. This inclined flange is disposed in lapped relation with the lower portion of the inclined outer wall of the rim of the hatch frame and is rigidly secured thereto preferably by means of a weld 19 of added metal that extends continuously along the top edge of said flange. Thus the rim of the hatch frame cooperates with the roof sheet to form a hollow upstanding rib on the roof around the upper end of the hatchway opening defined by said frame.

The hatch frame is provided with a unit cover and plug assembly comprising a hatch cover member 20, which seats on the rim of said hatch frame and is secured by suitable strap hinges 21 to the adjacent seam cap 10, and a tapered hatch plug member 22 sustained by said cover and having a compressible edge padding or packing 23 that seats against the converging walls of the hopper portion 16 of said hatch frame below the general

level of the roof. As shown in the drawing, the hatch cover has a wooden edge frame 24 and the hatch plug has a wooden edge frame 25 secured by bolts 26 to the cover frame. The combined hatch cover and plug has wooden bottom 27 and a metal top plate 28 with a filling of heat insulating material 29 therebetween. The metal top plate has a downwardly and outwardly inclined marginal flange 30 that overhangs but is clear of the downwardly and outwardly inclined outer wall of the hatch frame rim.

As shown in the drawing, the wooden edge frame 24 of the hatch cover 20 extends outwardly beyond the hatch plug 22 and has a sealing gasket 31 of rubber or other compressible material secured to the underside thereof, which gasket rests on a seat 32 provided therefor on the top of the hollow rim 17 of the metal hatch frame between the downwardly and outwardly inclined outer wall of said rim and the hopper portion 16 of said frame. The hatch cover seat forming portion 32 of the rim 17 of the hatch frame slopes or inclines inwardly and downwardly from the top of the downwardly and outwardly inclined outer wall of said rim to the hopper portion 16 of said frame, such angle being slightly greater than the angle of repose for ice, cinders and other material on the metal of said frame, but not so steep as to involve wedging of the upper gasket 31. In the accompanying drawing, the slope of the hatch cover seat is shown as about thirty degrees from the horizontal and this is quite ample to prevent lodging of ice and cinders, but as the angle of repose varies with different materials, the slope may be increased, say, to forty-five degrees to take care of such as might lodge at a lower angle. The overhanging outer marginal portion of the cover frame 24 has its under or gasket support surface beveled at an angle corresponding substantially to the angle of the sloping seat 32 provided therefor on the rim 17 of the hatch frame.

By the arrangement described, the combined hatch cover and plug forms a double closure for the hatchway opening, one at the upper end of the metal hatch frame and the other in the hopper portion thereof below the general level of the roof. The downwardly and inwardly sloping inner marginal portion of the rim of the hatch frame forms a flaring enlargement of the upper end of the hatchway opening that constitutes a beveled seat for the sealing gasket carried by the cover and prevents particles of ice, cinders and other material from lodging on said seat and preventing proper seating of said gasket and causing damage thereto. The downwardly sloping outer wall of

the rim portion of the hatch frame cooperates with the downwardly and inwardly sloping seat portion of said rim to form a substantially inverted V-shaped section which serves to stiffen and strengthen the upper end of the hatch frame and to prevent any accumulation of material around the mouth of the hatchway opening.

What I claim is:

1. A car roof having a hatch opening therein, a hatch frame in said opening and a cover for the upper end of said hatch frame, said end of said hatch being widely flared to provide a seat therein for said cover, the slant of said widely flared seat being slightly in excess of the angle of repose of cinders on the material of said seat but not so steep as to involve wedging of said cover in said seat.
2. A car roof having a hatch opening therein, a hatch frame in said opening and having a widely flaring seat at the upper end thereof and a closure for said frame comprising a cover member seated on said widely flaring seat and a plug member having wedging engagement with said frame below said widely flaring seat, the slant of said widely flaring seat being slightly in excess of the angle of repose of cinders on the material of said seat but not so steep as to involve wedging of said cover member in said seat.
3. A car roof having a hatch opening therein, a metal hatch frame in said opening, a cover for the upper end of said hatch frame and a sealing gasket on the underside of said cover, said end of said hatch frame being widely flared to provide a seat therein for said gasket and thence inclined outwardly and downwardly to provide a downwardly opening rim around said seat, the slant of said widely flared seat being slightly in excess of the angle of repose of cinders on the hatch frame metal but not so steep as to involve wedging of said gasket in said seat.
4. A car roof having a hatch opening therein, a metal hatch frame in said opening and a closure member for the upper end of said frame comprising a cover member having a gasket on its underside and a plug member having wedging engagement with said frame below said cover member, said upper end of said frame being widely flared to provide a seat for said gasket and thence inclined outwardly and downwardly to provide a downwardly opening rim around said seat, the slant of said seat being slightly in excess of the angle of repose of cinders on the hatch frame metal but not so steep as to involve wedging of said gasket in said seat.

LOYD E. CARTMILL.
